United States Patent

Des. 240,214
Patented June 8, 1976

240,214

INVALID'S WALKER

Lillie C. Allen, 1821 5th St., Portsmouth, Ohio 45662

Filed Aug. 20, 1975, Ser. No. 606,303

Term of patent 14 years

Int. Cl. D12—12

U.S. Cl. D12—130

FIG. 1

FIG. 2

FIG. 3

FIG. 1 is a perspective view of an invalid's walker showing my new design;

FIG. 2 is a side elevational view;

FIG. 3 is a top plan view;

FIG. 4 is a rear elevational view; and

FIG. 5 is a perspective view thereof in its open, patient-admitting condition.

I claim:

The ornamental design for an invalid's walker, substantially as shown.
